TAKE-UP MECHANISMS FOR SEWING
MACHINES

Max L. Waterman, Fairfield, Conn., assignor to
The Singer Manufacturing Company, Elizabeth,
N. J., a corporation of New Jersey

Application June 29, 1935, Serial No. 28,996

10 Claims. (Cl. 112—241)

This invention relates to improvements in thread take-up mechanisms for sewing machines and more particularly in needle-thread take-ups, the invention having for its object to provide for ready manufacture of a durable thread take-up mechanism capable of efficiently meeting high speed requirements of operation.

With the above and other objects in view, the invention comprises the devices, combinations and arrangements of parts hereinafter described in connection with the accompanying drawing which illustrates a preferred embodiment of the invention, from which the several features of the invention and the advantages attained thereby will be readily understood by those skilled in the art.

In the accompanying drawing, Fig. 1 is a front end elevation of the bracket-arm head and bed-plate of a sewing machine containing the improved needle-thread take-up mechanism. Fig. 2 represents a vertical section of the bracket-arm head of the machine. Fig. 3 represents an enlarged vertical section of the universal-joint connections between the take-up lever and its actuating crank-member. Fig. 4 represents a horizontal section of the connections illustrated in Fig. 3. Fig. 5 represents a perspective view of the pivot-block of the universal-joint connection.

Referring to the drawing, the sewing machine frame includes the usual bed-plate or work-support 1 and a bracket-arm terminating at its free end in a head 2 which overhangs the work-support.

Rotatably journaled in the bracket-arm 1 is a horizontally disposed actuating shaft 3 carrying a counterweighted crank-arm 4 provided with a crank-pin 5. Pivots embracing the crank-pin 5 is the upper bearing-boss 6 of a needle-bar link 7 having its lower bearing-boss 8 pivotally embracing a stud-pin 9 extending from a split collar 10 which is clamped upon the upper end of a needle-bar 11. The needle-bar 11 is journaled for vertical reciprocation in a bearing bushing 12 suitably secured in the bracket-arm head 2, the needle-bar carrying at its lower end a needle 13.

Cooperating with the needle 13, below the work-support 1, is a loop-taker 14 which in the present instance is of the horizontal-axis rotary hook type adapted to cast loops of needle-thread about a mass of under thread contained in a bobbin-case 15.

The work is intermittently advanced by a drop-feed mechanism including a feed-dog 16 operating through the throat-plate 17 upon the work-support. Yieldingly opposed to the feed-dog is a

presser-foot 18 carried by the usual spring-pressed presser-bar 19 vertically movable in the bracket-arm head 2.

The present invention resides more particularly in the needle-thread take-up mechanism and while, in its preferred embodiment, it is in the nature of an improvement on the take-up forming the subject of the U. S. patent to W. F. Dial et al., No. 695,915, Mar. 25, 1902, it is to be understood that the invention, as defined by the appended claims, is not restricted to the specific type of take-up herein described and illustrated in the accompanying drawing.

According to the present construction, the upper end of the needle-bar link 7 carries a bearing member in the form of an auxiliary bearing-boss 20 adjacent and substantially parallel to the bearing-boss 6 of said link. Journaled in said bearing-boss 20, for pivotal and bodily endwise movements therein, is a stud-pin 21 having a circular head 22, providing a shoulder 23 which serves to limit inward movement of the stud-pin 21. Embracing the stud-pin head 22 is a collar 24 provided with diametrically aligned apertures 25, said collar being fixedly secured upon the head 22 by a screw 26.

The stud-pin head 22 is diametrically provided with a guide-slot presenting parallel side walls 27 confining therebetween a pivot-block 28 having spherically rounded upper and lower ends 28' in engagement with the collar 24. The pivot-block 28 is provided with a guide-aperture 29 terminating in the spherical ends of said block and slidably receiving a guide-rod 30 passing through the collar apertures 25, said apertures 25 being slightly larger than the diameter of the guide-rod 30 to provide for and limit tilting movements of the pivot-block.

The guide-rod 30 constitutes the depending arm of a two-armed take-up lever, of which the other arm 31 extends forwardly through a suitable slot in the bracket-arm head 2 and adjacent to the usual guard-flange 32, the arm 31 of said lever being provided with the usual thread-eye 33. Intermediate the arms 30 and 31 thereof, the take-up lever has a bearing hub 34 pivotally journaled upon a headed fulcrum-pin 35 disposed substantially parallel to the rotation axis of the actuating shaft 3 and to the pivotal axes afforded by the crank-pin 5 and the stud-pin 21. The fulcrum-pin 35 is suitably secured in an aperture in the frame head 2 by means of a set-screw 36. The take-up lever performs its usual function of controlling the needle-thread in the formation and setting of stitches.

One of the outstanding problems in the sewing machine art has been the provision of an efficient take-up mechanism capable of withstanding the wear incidental to operation of a sewing machine at a speed at least equal to 4000 stitches per minute. The crank-and-link type of take-up presents lubrication difficulties, because of the bodily travel of the actuating connections for the take-up lever and the fact that an excess of lubricant may lead to soiling of the thread or the work. The present invention minimizes excessive lubrication requirements by the elimination of undesirable cramped conditions in the actuating connections for the take-up lever, which cramped conditions may arise from slight variations from true parallel relationship of the axes 3, 5, 21 and 35, and from any departures from the correct angular relationship between the axis 21 and the guide-rod 30.

According to the present invention, the tilttable pivot-block 28 and the pivotal connection between the bearing-boss 20 and the stud-pin 21, comprise universal-joint connections with the take-up lever which eliminate the extreme precision requirements difficult to maintain under mass production. As the axis 35 of the take-up lever is fixed, in the present arrangement, the take-up lever 30, 31 vibrates in a single plane. Should the axis of the take-up lever 30, 31 be not in perfect parallelism with the axis of its actuating crank-member, the plane of vibration of the take-up lever will be slightly inclined to the horizontal axis of the shaft 3. To accommodate this condition, the stud-pin 21 is free to move endwise in the crank bearing-boss 20. Thus, the take-up lever actuating connections automatically assume free driving relations and therefore may operate with a minimum of friction and consequent minimum heating and wear at high speed operation.

Having thus set forth the nature of the invention, what I claim herein is:—

1. Thread take-up mechanism for sewing machines comprising, a pivotally mounted take-up lever, and supporting and actuating means for said lever including a crank-member, a connection-element freely movable in a direction substantially parallel to the turning axis of said crank-member, and a universal-joint connection incorporated in said means.

2. Thread take-up mechanism for sewing machines comprising, a take-up lever, and supporting and actuating means for said take-up lever including a crank-member, and relatively transversely pivoted connections incorporated in said means.

3. Thread take-up mechanism for sewing machines comprising, a take-up lever, and supporting and actuating means for said take-up lever including a connection-element freely movable endwise, and relatively transversely pivoted connections incorporated in said means.

4. Thread take-up mechanism for sewing machines comprising, a pivotally mounted take-up

lever provided with a thread-eye, a rotary crank-member, a pivot-block in sliding engagement with said take-up lever, and relatively transversely pivoted connections between said crank-member and pivot-block.

5. Thread take-up mechanism for sewing machines comprising, a pivotally mounted take-up lever provided with a thread-eye and having a guide-rod, a rotary crank including a pivotal and endwise movable connection-element and a pivot-block in sliding engagement with said guide-rod and fulcrumed upon said connection-element for pivotal movement about an axis transverse to the pivotal axis of the connection-element.

6. Thread take-up mechanism for sewing machines comprising, a pivotally mounted take-up lever, a connection-element provided with a guide-slot, a pivot-block tiltably disposed in said guide-slot and slidably engaging said take-up lever, and a bodily rotatable support for said connection-element providing for pivotal and bodily endwise movements thereof.

7. Thread take-up mechanism for sewing machines comprising, a rotary crank-pin, a bearing member pivotally carried by said crank-pin, a stud-pin supported by said bearing member for pivotal and bodily endwise movements, a pivot-block fulcrumed upon said stud-pin for pivotal movement about an axis transverse to the pivotal axis of the stud-pin, a take-up lever provided with a thread-eye and having an arm slidably engaged by said pivot-block, and a pivotal support for said take-up lever.

8. Thread take-up mechanism for sewing machines comprising, a rotary crank-pin, a bearing member pivotally carried by said crank-pin, a stud-pin supported by said bearing-member for pivotal and bodily endwise movements, said stud-pin having a head provided with a guide-slot, an apertured pivot-block tiltably disposed in the guide-slot of the stud-pin head and fulcrumed upon said head for pivotal movement about an axis transverse to the pivotal axis of said stud-pin, a take-up lever provided with a thread-eye and having an arm slidably embraced by said pivot-block, a pivotal support for said take-up lever, and means carried by said stud-pin head for limiting tilting movement of said pivot-block.

9. Thread take-up mechanism for sewing machines, comprising a pivotally mounted take-up lever having a guide-rod arm, a guide member slidably embracing said arm, a crank member, and universally jointed connections between said crank and guide members.

10. Thread take-up mechanism for sewing machines, comprising a pivotally mounted take-up lever having a guide-rod arm, a guide member slidably embracing said arm, a crank member having a turning axis substantially parallel to the pivotal axis of the take-up lever, and universally jointed connections between said crank and guide members.

MAX L. WATERMAN.
